 (Continued)*Primary Examiner* — Selina Sikder*(74) Attorney, Agent, or Firm* — ScienBiziP, P.C.(57) **CLAIM**

The ornamental design for a road side-unit as shown and described.

DESCRIPTION

FIG. 1 is a perspective view of a road side-unit;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

Lines having a long dash followed by two shorter dashes indicate tangent edges.

The broken lines in the drawings portions of the road side-unit that form no part of the claimed design.

1 Claim, 8 Drawing Sheets(56)
